[57] CLAIM

The ornamental design for an electronic computer, as shown and described.

DESCRIPTION

FIG. 1 is a perspective view of the top, front and right side of an electronic computer with the cover open, showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a perspective view similar to FIG. 1, with the compact disk holder in the extended position;

FIG. 9 is a front elevational view with the cover closed;

FIG. 10 is a top plan view thereof;

FIG. 11 is a right side elevational view thereof; and,

FIG. 12 is a perspective view of the front, top and right side thereof.
